UNITED STATES PATENT OFFICE

PHILIP M. BRATTEN, OF FORT WORTH, TEXAS, ASSIGNOR, BY MESNE ASSIGNMENTS, TO
FRIGIDAIRE CORPORATION, A CORPORATION OF DELAWARE

REFRIGERATING APPARATUS

Application filed April 30, 1927. Serial No. 187,929.

This invention relates to mechanical refrigeration and particularly to mechanically refrigerating devices for cooling various type of commercial refrigerator cabinets such 5 as show-case refrigerators.

One object of the invention is to improve the efficiency of the transfer of heat from the circulating air of the cabinet to the metal walls of the refrigerating device by substantially preventing accumulation of frost thereon, and to improve the efficiency of thermal transfer between the metal walls to the refrigerant, whereby refrigeration may be effected more efficiently and economically 10 than heretofore. In the present invention this object is accomplished by a novel arrangement of air flues and brine ducts to be described.

Further objects and advantages of the 20 present invention will be apparent from the following description, reference being had to the accompanying drawings, wherein a preferred form of embodiment of the present invention is clearly shown.

25 In the drawings:

Fig. 1 is vertical longitudinal sectional view of a show-case refrigerator cabinet equipped with a refrigerating device embodying the present invention;

30 Fig. 2 is a top view partly broken away, of the device; and

Fig. 3 is a sectional view on the line 3—3 of Fig. 2.

35 In Fig. 1, 20 designates a cabinet having solid insulating walls 21, 22 and 23 and other insulating walls provided by dead air spaces between a plurality of plates of glass 24 and 25. A partition 26 divides the interior of the cabinet into a cooling compartment 28 40 and a food or other display compartment 27.

The refrigerating device 30 includes a shell 45 brine tank made of tin-plated copper or galvanized iron and formed to provide a main brine chamber, reservoir or body portion 31 and a sheet metal shell or shells, the walls of which provide relatively large air flues 35, 36 and 37. These shell type walls are hollow to provide relatively narrow brine ducts or chambers 32, 33 and 34 which communicate with the body portion 31.

The body portion or chamber 31 is provided with a tightly fitting removable cover 38 and encloses a cooling unit herein shown as an evaporator comprising a header or boiler 40 connected with refrigerant ducts 41. One end of the boiler 40 extends through an opening 42 in the outside wall of the chamber 31 and is secured by a flanged collar 43, a clamping disc 44 forming one end of the boiler, and by screws 45. Pipes 46 and 47 conduct refrigerant respectively into and out of the boiler 40. The chamber and ducts should be filled with brine or other low freezing-point liquid up to about one inch below the top of the container and the boiler should not be located too low in the chamber 31, otherwise only the brine at the lower levels will effectively circulate and be cooled. Preferably the top of the boiler should be about one inch below the level of the brine.

It has been found that with a cooling unit located low in a deep tank, the brine above the unit does not cool down to the temperature desired, it remaining above the freezing point even when the rest of the brine may be at or below freezing temperature.

The boiler 40 should be level in order that the float valve therein (not shown), which controls the flow of refrigerant to the unit, may operate properly. This is done by metal wedges 60 adapted to rest upon the bottom wall of the tank 31 and to engage the lower portions of the loop-ducts 41. The wedges 60 may be secured in the desired position by soldering.

The device 30 is supported above the bottom of the cooling chamber 28 and is spaced from the chamber walls and baffle 26 so that air may circulate freely around the device as well as through its flues. Preferably, the combined surface of the exposed vertical walls of the device should at least be equal to the exposed surface of the block of ice which would be required to cool the cabinet. By providing relatively narrow brine ducts and relatively large flue openings, a relatively greater exposed area may easily be provided by a refrigerating device which will occupy a smaller space than the ice block. The space required by the device need be no

more than approximately two-thirds of the cubical content of the cooling chamber 28, and may be slightly less if necessary to provide at least three inches of space between the 5 walls of the device and the cooling chamber walls so that air may circulate freely about and through the unit. The matter of clearance is important, because frosting of the tank and ducts tends to decrease the clearance and 10 might even close it off entirely, preventing free circulation of the air. Unless the air can circulate freely adjacent the walls of the refrigerating device, it can not absorb the heat from the air. For the same reason the 15 flue openings should be relatively wide.

The circulation of air within the cabinet is indicated roughly by the arrows 50, 51, 52 and 53. Shelves or other baffles (not shown) may be provided in the food chamber 27 for 20 securing a fairly even distribution of the air circulating therein.

If more than one refrigerating device is used in a cooling chamber, at least four inches and preferably six inches should be left between the devices for circulation and to prevent the space from being stopped up with frost.

One of the features of the present invention is the use of such a relatively large 30 metal, heat-absorbing surface adjacent which the air may circulate freely, that it is possible to effect satisfactory refrigeration by brine or other heat transfer medium working at temperatures higher than permissible in 35 brine tanks used heretofore. Although, during the active period of operation of the refrigerating machine frost may collect upon the metal surface, these surfaces will be defrosted during the idle periods of the machine. Thus hindrance by frost to the transfer of heat to the metal surfaces is much less than in case of brine tanks used heretofore.

Another feature is the circulation of brine 45 through relatively narrow ducts between the metal, heat-absorbing surfaces. Substantially all of the brine which is cooled by the evaporator is caused to circulate actively so that heat will be conducted from the metal walls to the evaporator more rapidly than heretofore, with the result that the duration 50 of the active period of the refrigerating machine is reduced.

It is therefore apparent that refrigeration 55 can be obtained more economically than heretofore because the heat transferring media, the metal walls and the brine, are caused to operate more efficiently, and because the machine is not required to reduce the pressure upon the refrigerant to the low point necessary heretofore, since the average brine temperature is higher.

I have discovered also that a cabinet can be cooled most effectively and economically 65 by mechanically refrigerated circulating brine when the refrigerating device contain-

ing the brine occupies about two-thirds of the cubic capacity of the cooling compartment or chamber used formerly for receiving ice-blocks, and when the ducts and flues of the unit are so constructed and arranged as to give the maximum cooling surface with the minimum brine. Large heat transfer surface results in reduction of the space required for the cooling unit. Therefore, the compartment for receiving the device may be made smaller. Large flues permit free circulation of air. 75

The refrigerating device may be provided with horizontal or vertical flues according to the type of refrigerator cabinet with which they are intended to be used. Vertical flues are preferable, owing to the natural tendency of air to descend on being chilled. However, the invention is not limited to refrigerating devices or tanks with vertical flues, as a cooling unit with horizontal flues may be used advantageously in some types of cabinets; for example, a show-case cabinet not provided with a baffle to separate the food compartment from the cooling compartment. 80

Where the term "brine" is used in the specification and claims, it refers to any low freezing point liquid or solution which is suitable for transferring heat from the heat transfer walls of the refrigerating device to the 85 evaporator. 90

As an example of construction of one form of the invention, if the tank and ducts are made of sheet metal sufficiently thin to permit making the joints by lock-seaming and soldering, I prefer to provide ducts only one inch or less wide. If heavier sheet material is required on account of the size of the cooling unit, and the joints must therefore be riveted, the ducts may be two inches wide to 100 allow for introducing riveting tools between the metal sheets forming the ducts. There is no object in making the ducts wider than one inch except to facilitate manufacture. Generally, the brine ducts should be from 105 about one to two inches wide and the flues preferably at least four times as wide as the ducts. 110

While the form of embodiment of the present invention as herein disclosed, constitutes a preferred form, it is to be understood that other forms might be adopted, all coming within the scope of the claims which follow. 115

What is claimed is as follows: 120

1. A cooling device for refrigerators comprising, a tank including a body portion adapted to contain brine, and a plurality of shell type hollow walls forming narrow circulating ducts communicating with the body portion, said walls providing one or more flues for circulating air, and a cooling unit within the body portion for cooling the brine. 125

2. A cooling device for refrigerators comprising, a tank including a body portion 130

adapted to contain brine, and a plurality of vertically extending shell type hollow walls forming narrow circulating ducts communicating with the body portion, said walls providing one or more vertically extending flues for circulating air, and a cooling unit within the body portion for cooling the brine.

3. A cooling device for refrigerators comprising, a tank including a body portion adapted to contain brine, and a plurality of shell type hollow walls forming narrow circulating ducts communicating with the body portion, said walls extending in a plurality of directions from the body portion and providing a plurality of flues for circulating air, and a cooling unit within the body portion for cooling the brine.

4. A cooling device for a refrigerator comprising a sheet metal shell forming a main chamber for brine, an evaporator within the chamber for cooling the brine therein, certain walls of said shell being hollow and forming relatively narrow chambers, said narrower chambers branching from and communicating with the main brine chamber and arranged to form a flue for cooling circulating air.

5. A cooling device for a refrigerator comprising a sheet metal shell forming a main chamber for brine, an evaporator within the chamber for cooling the brine therein, certain walls of said shell being hollow and forming relatively narrow chambers, said narrower chambers branching from and communicating with the main brine chamber, said hollow walls being arranged to provide a plurality of flues, one of said walls being common to a plurality of said flues.

6. A cooling device for a refrigerator comprising a sheet metal shell forming a main chamber for brine, an evaporator within the chamber for cooling the brine therein, certain walls of said shell being hollow and forming relatively narrow chambers, said narrower chambers branching from and communicating with the main brine chamber and arranged to form a flue for cooling circulating air, the cross sectional area of the refrigerating medium chambers formed by the hollow walls being less than cross sectional area of the flue formed by such walls.

7. A cooling device for a refrigerator comprising a sheet metal shell forming a main chamber for brine, an evaporator within the chamber for cooling the brine therein, certain walls of said shell being hollow and forming relatively narrow chambers, said narrower chambers branching from and communicating with the main brine chamber, said hollow walls being arranged to provide a plurality of flues, one of said walls being common to a plurality of said flues, the cross sectional area of the refrigerating chambers formed by the hollow walls being less than

the cross sectional area of the flues formed by such walls.

8. A cooling device for refrigerators comprising a tank including a main brine chamber adapted to contain brine, and a plurality of shell type hollow walls forming narrow circulating ducts communicating with the main chamber, said walls extending in a plurality of directions from the chamber and providing a flue for circulating air, and a cooling unit within the main chamber for cooling the brine.

9. A cooling device for refrigerators comprising a tank including a main brine chamber adapted to contain brine, and a plurality of shell type hollow walls forming narrow circulating ducts communicating with the main chamber, said walls providing one or more flues for circulating air and a cooling unit within the main chamber for cooling the brine, the cross sectional area of the circulating ducts formed by the hollow walls being less than the cross sectional area of the flue formed by such walls.

In testimony whereof I hereto affix my signature.
